(57) **CLAIM**

The ornamental design for a sprinkler head cover, as shown and described.

DESCRIPTION

FIG. 1 is a perspective view of a sprinkler head cover showing the new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof.

FIG. 8 is another perspective view showing the sprinkler head cover; and,

FIG. 9 shows a sprinkler head with the sprinkler head cover. The broken lines in the drawing depict environmental subject matter only and form no part of the claimed design.
